UNITED STATES PATENT OFFICE.

ALPHEUS F. S. LYONS, OF NEENAH, WISCONSIN.

BOOT AND SHOE.

Application filed November 17, 1920. Serial No. 424,767.

To all whom it may concern:

Be it known that I, ALPHEUS F. S. Lyons, a citizen of the United States, residing at Neenah, in the county of Winnebago and State of Wisconsin, have invented certain new and useful Improvements in Boots and Shoes, of which the following is a specification.

My invention relates to boots and shoes and particularly to foxed shoes having cloth tops, the object thereof being to provide an improved shoe of the class indicated.

My improved shoe is of that class of foxed shoes which comprise a top or upper whose vamp and quarter are both made from cloth or the like and the distinguishing feature of my invention consists in stitching, or otherwise fastening, two relatively narrow side braces of leather or the like in position upon the outer sides of the lower marginal portions of the upper or top, one at each side thereof, so as to reinforce and protect the lower portion of said top or upper at each side thereof and make it possible to bottom the shoe with a leather sole. In the best form of my invention the two lower marginal side braces terminate at their forward ends a short distance to the rear of the toe and said ends are covered by a tip or toe cap fastened to the vamp after said side braces have been applied to the upper, while at their rear ends said side braces terminate a short distance forward of the rear end of the shoe and said ends are disposed beneath a counter cover that is secured to the quarter of the top or upper after said braces have been applied.

Other features of my invention are hereinafter pointed out.

40 In the accompanying drawings:

Figure 1 is a side elevation of a shoe constructed in accordance with my invention.

Figure 2 is a section on line 2—2 of Fig. 1.

Figure 3 shows a modification.

45 Having reference to the drawings, 1 represents the cloth quarter of the top or upper of the shoe and 2 the usual cloth vamp thereof, said two parts usually being two separate pieces of cloth fastened together by stitches, and a side brace 3 of leather being applied to cover the joint between the vamp and quarter as well as to connect said parts.

To the exterior of each side of the top or upper 1—2 I apply a relatively narrow side brace 3 of leather or other suitable material,

that is disposed longitudinally along the lower marginal portion of said upper and fastened along its top edge to the vamp and quarter by stitches 4. At their forward ends 60 the side strips 3 terminate a short distance to the rear of the toe of the shoe and at their rear ends a short distance forward of the rear end of the shoe. After applying the side brace 3 I next apply a counter covering 65 5 and a tip, or toe cap, 6, said covering and tip being fastened to the vamp and quarter, as well as to the ends of the strips 3, by stitches 7 and 8, respectively. The counter covering 5 overlies and covers the rear end portions 70 of strips 3 while the tip 6 overlies and covers the forward end portions of said strips.

The bottoming of the shoe may be carried out either according to the McKay or the Goodyear welt processes. As shown in Fig. 75 2 the first mentioned process is employed, the lower marginal portion of the cloth upper together with the lower marginal portions of both side braces 3, being turned inwardly between an innersole 9 and outersole 80 10 to which they are fastened by stitches 11 which also fasten the two soles together. When the shoe is bottomed according to the Goodyear welt process as shown in Fig. 3, the lower marginal portions of the upper 85 and of strips 3, together with a welt strip 12 are sewed to an innersole 13 and thereafter the welt strip 12 is sewed to the usual outersole 14.

As will be clear, the longitudinal side 90 braces 3 extend upwardly above the inseam 15 far enough to shield and reinforce that portion of the cloth upper that is just above the outersole 14 which is the part of the upper that is subjected to the hardest 95 usage. Also the provision of the strips 3 greatly reinforces the lower edge of the cloth upper and adapts the latter to be sewed to the bottom parts of the shoe. Furthermore, these side strips greatly improve the appearance of shoes of this class as well as being a protection to the upper; a valuable asset in soling and resoling, and a decided benefit to the public who wears the shoe. Therefore, constitutes the invention a valued 100 improvement in shoe construction. This side brace may be in one or two parts.

What I claim is:

1. A boot or shoe of the character described comprising a top whose vamp and quarter are separate pieces of cloth joined along a line extending across the instep; a

leather strip covering the joint between the 5
vamp and quarter and stitched to both of
said parts; two relatively narrow longitudinally
disposed leather side braces fastened
in position upon the outer sides of the lower
marginal portions of said top and overlying
the ends of said strip, one at each side of the
top; a toe cap overlying the forward ends
of said side braces; a counter cover overlying
10 the rear ends of said side braces; stitches
securing the toe cap to said top and to said
forward ends and the counter cover to said
top and said rear ends, and an outer sole,
the lower marginal portions of said top and
15 said side braces being turned inwardly to-
gether above said outer sole and both fas-
tened to the latter.

2. A boot or shoe of the character de-

scribed comprising a top whose vamp and
quarter are both made of cloth; two separate 20
relatively narrow longitudinally disposed
side braces of leather fastened in position
upon the outer sides of the lower marginal
portions of said top, one at each side there-
of; a toe cap overlying the forward ends of 25
said side braces; a counter cover overlying
the rear ends of said side braces; stitches se-
curing the toe cap to said top and to said
forward ends and the counter cover to said
top and to said rear ends; an innersole; an 30
outer sole between which and said innersole
the lower marginal portions of said top and
said side braces extend inwardly, and
stitches fastening said inturned portions of
said top and braces to said innersole.

ALPHEUS F. S. LYONS.
